UNITED STATES PATENT OFFICE.

PEREZ M. STEWART, OF NEW YORK, N. Y., ASSIGNOR TO GERTRUDE F. STEWART, OF NEW YORK, N. Y.

COMPOSITE SLAB FOR BUILDING PURPOSES.

1,308,306.

Specification of Letters Patent.

Patented July 1, 1919.

Application filed May 15, 1917. Serial No. 168,659.

To all whom it may concern:

Be it known that I, PEREZ M. STEWART, a citizen of the United States, and residing in the borough of Manhattan, in the city, county, and State of New York, have invented an Improvement in Composite Slabs for Building Purposes, of which the following description, in connection with the accompanying drawings, is a specification, like characters on the drawings representing like parts.

This invention relates to a composite slab which is especially designed among other uses to be employed as a tile or roofing slab. The invention has for its object to provide a composite slab which is light in weight, so that it can be easily handled, which is strong so as to resist fracture in handling, and which resists fire, fumes, climatic changes, etc.

To this end, the composite slab is provided with a body portion of gypsum or like substantially light, non-metallic cementitious substance, which body portion is provided with a plurality of openings extended through it which are filled with a reinforcing non-metallic material, such as concrete, which forms reinforcing bars or sections of non-metallic cementitious material enveloped by and bonded with the lighter non-metallic material, and the concrete bars are provided with a metal reinforcement extended through and enveloped by them. The composite slab or tile thus produced may be used to advantage, but it is preferred to provide the same with a layer of asbestos or like fibrous material on one or both surfaces, and when used on only one surface to provide the other surface with a waterproof adhesive composition or coating.

The metallic reinforcing members of adjacent tiles or slabs may be tied together and embedded in a bar of plastic non-metallic material, such as gypsum or concrete as is preferred, or they may be secured to the supporting frame of the building.

These and other features of this invention will be pointed out in the claims at the end of this specification.

Figure 1 is a plan of a portion of a roof provided with tiles or slabs embodying this invention.

Fig. 2, a section on the line 2—2, Fig. 1, and

Fig. 3, a section on the line 3—3, Fig. 1.

Referring to the drawing, 10 represents the body portion of a composite slab or tile embodying this invention, said body portion being composed of gypsum or like light, non-metallic cementitious material, which is provided with preferably a plurality of holes or openings 12 extended, for the best results, through the body portion 10 from side to side or from end to end, and preferably arranged parallel to one another and in substantially close proximity to one another.

The body portion 10 of gypsum or like material, while light, is more or less fragile and liable to be broken, and to overcome this I have provided the said body portion with a reinforcement of concrete cementitious material which fills the openings 12, bonds with the body portion 10, and forms within the body portion 10 a series of reinforcing bars 13 of non-metallic material, which bars in turn are reinforced by metal rods, wires, or the like, 14, which preferably extend beyond the ends of the concrete bars 13 and may and preferably will be provided with bends or eyes 15 at their ends for a purpose as will be described.

The reinforced slab may and preferably will be provided on one face or surface with a layer 16 of fibrous material, preferably asbestos paper or felt or the like, which is preferably waterproofed and which serves as a protector for the tile against acid and alkali fumes and moisture, and said layer may and, preferably will be bonded to the body portion 10 of the slab or tile.

The composite slabs or tiles thus formed may and preferably will be laid upon the roof of a building with adjacent tiles spaced apart and with the reinforcing rods 14 substantially in line with each other, so that they may be tied together by wires 21, and when thus tied, the space between adjacent tiles may be filled in with concrete 22 or other plastic material, which not only protects the metal connections 21 and the projecting ends of the metal reinforcing rods 14, but also bonds adjacent tiles together, as represented in Figs. 1 and 3.

In practice, the asbestos layer 16 may be laid in the mold in which the hollow body

portion 10 is formed, so that the plastic gypsum may be bonded to the asbestos or other fibrous layer, and the hollow body portion may be formed by means of suitable cores, 5 not shown, but which are removed while the body portion of gypsum is in a partially set condition, and when the gypsum has fully set, the body portion 10 with the fibrous layer 10 adhering thereto, may then be removed from the mold and the metal reinforcing rods or wires 14 extended through the openings 12 and the latter filled with concrete or other plastic material of greater strength than the body portion 10 to form the bars 13. Instead 15 of this particular method of forming the composite slab, the reinforced concrete bars may be first formed, placed in the mold and the gypsum then poured or otherwise placed in the mold so as to embed the reinforced 20 concrete bars in the gypsum body portion.

The composite slab is herein described as a tile and while it is well adapted for such use, it is not desired to limit the invention in this respect, as the slab can be made of

any size and used for other purposes, as, for 25 instance, a ceiling, wall or other slab.

The upper or exposed surface of the slab may and preferably will be given a coat 20 of asphalt or other adhesive material, after the slab has been allowed to dry out in the 30 shop.

Claims:

1. A composite slab comprising a body portion of substantially light relatively fragile plastic material, a section of plastic cementitious material of greater strength embedded in said body portion and bonded therewith, and a metal reinforcement embedded in said section. 35

2. A composite slab comprising a body portion of gypsum, a plurality of sections of concrete located in said body portion and bonded therewith, and a metal reinforcement embedded in said concrete. 40

In testimony whereof, I have signed my 45 name to this specification.

PEREZ M. STEWART.
